TILLER HOUSING

John W. Davies III, Plymouth, Wis., assignor to Gilson Bros. Co., Plymouth, Wis., a corporation of Wisconsin

Filed Oct. 28, 1964, Ser. No. 82,367

Term of patent 14 years

(Cl. D40—1)

FIGURE 1 is a perspective view of a tiller housing embodying the present invention as applied to a rotary tiller.

FIGURE 2 is an enlarged perspective view of the tiller housing per se.

FIGURE 3 is a cross section taken along the line 3—3 of FIGURE 2.

FIGURE 4 is a fragmentary cross section taken along the line 4—4 of FIGURE 2.

The dotted line showing is for illustrative purposes only.

I claim:

The ornamental design for a tiller housing, as shown and described.
